SLEEPING UNIT

Forest Wilson, Chicago, Ill.

Application June 13, 1955, Serial No. 36,494

Term of patent 14 years

(Cl. D5—4)

FIG. 1

FIG. 2

FIG. 3

FIG. 4

Fig. 1 is a perspective view of a sleeping unit embodying my new design;

Fig. 2 is a front elevational view of the sleeping unit of Fig. 1;

Fig. 3 is a plan view of the sleeping unit of Fig. 1; and

Fig. 4 is a side elevational view of the sleeping unit of Fig. 1.

The dominant features of the design reside in the portion shown in full lines on the drawing.

I claim:

The ornamental design for a sleeping unit, substantially as shown and described.
